CLAIM

The ornamental design for a blind hole threaded exact point center locator, as shown and described.

DESCRIPTION

FIG. 1 is a perspective view of the blind hole threaded exact point center locator;

FIG. 2 is a front elevational view of FIG. 1;

FIG. 3 is a rear plan view of FIG. 1;

FIG. 4 is a right elevational view of FIG. 1;

FIG. 5 is a left elevational view of FIG. 1;

FIG. 6 is a top elevational view of FIG. 1; and,

FIG. 7 is a bottom plan view of FIG. 1.
